UNITED STATES PATENT OFFICE.

WILLIAM WEST, OF MADISONVILLE, OHIO.

APPARATUS FOR CARBURETING AIR OR GASES FOR ILLUMINATING PURPOSES.

SPECIFICATION forming part of Letters Patent No. 231,635, dated August 24, 1880.
Application filed March 30, 1880. (No model.)

To all whom it may concern:

Be it known that I, WILLIAM WEST, a citizen of the United States, residing at Madisonville, Hamilton county, Ohio, have invented 5 new and useful Improvements in Apparatus for Carbureting Air or Gases for Illuminating Purposes, of which the following is a specification.

The hydrocarbon fluids ordinarily used for carbureting air or gases for illuminating purposes are composed, as is well known, of liquids of different specific gravities, of which the lighter and more volatile, and consequently richest for the purpose, are in the methods 10 and apparatus at present employed generally first consumed, leaving the heavier and poorer portions as a residue practically wasted. In this use of the fluids the light produced is of a constantly-decreasing brilliancy until a fresh 15 supply of the fluid is put into the carbureter and the result repeated.

It is the object of my invention to remedy this difficulty and provide an apparatus whereby the hydrocarbon fluid may be preserved at 20 a uniform gravity while being used for this purpose, thereby maintaining a light of uniform intensity until the liquid is entirely consumed.

To this end my invention consists in the improved apparatus for utilizing hydrocarbon fluids in carbureting air or gases, as more fully hereinafter described, and pointed out in the 25 claims.

My invention is embodied in mechanism 30 illustrated in the drawings, in which Figure 1 is a vertical section of my improved carbureter, showing its chambers and connections. Figs. 2 and 3 are plan sections, on a somewhat reduced scale, taken on the lines $x x$ and $y y$ 35 respectively.

Similar letters of reference indicate like parts throughout the drawings.

A in the drawings is the carbureter, which is substantially of cylindrical form and divided into three main sections or compartments—B, the condensing or purifying chamber; C, the carbureter proper, and D, the receiving and settling tank.

The chamber C may be divided into any 40 number of compartments, separated by horizontal partitions c . The space in each com-

partment is occupied by carbureting-chambers E and fluid-distributing reservoirs F.

The carbureting-chambers E are substantially in the form of a continuous return-channel arranged transversely across each compartment and communicating at opposite ends by openings d' with the compartments above and below, thus forming a substantially continuous channel or carbureting-chamber, divided by the vertical partitions e into return-channels, communicating at alternate ends. The air or gas to be carbureted enters at the lower terminus of the carbureting-chamber at h , and after traversing the entire series of 65 channels emerges into the condensing and purifying chamber B, and thence by pipe M to the service-pipes.

I use sponge or other suitable material in the carbureting-chambers as an absorbent, 70 which, by capillary attraction, takes up the hydrocarbon fluid, and thus exposes it in a highly-divided state to the air or gas by which it is to be absorbed, thereby more thoroughly saturating and carbureting the air or gas for 75 illuminating purposes.

Interposed between the return-channels constituting the carbureting-chambers E are the reservoirs F, which consist, also, of return-conduits arranged transversely across each 80 compartment between the carbureting-chambers E, and communicating at each end with the exterior channel, F', in each separate compartment. Overflow-pipes g are arranged at alternate sides of the compartments to take 85 any excess of liquid supplied to the upper chambers into those below successively, and from the lowest of the series into the receiving-tank D.

In the present illustration of my invention 90 the channels F are formed by side walls, $f f$, and a top wall, f' , upon which latter the partitions e rest. Tight joints are made at all points of connection of the dividing-partitions, excepting where the side walls, $f f$, rest upon 95 the floor of the compartment, where a narrow slit or series of openings is left, through which the hydrocarbon liquid passes into the carbureting-chambers, thus supplying them uniformly throughout their entire length.

The height of the overflow-pipes g above the floor of each compartment determines the 100

height to which the liquid can rise therein, any excess passing downward from one compartment to another and into the receiving reservoir D.

5 The form of the distributing-reservoirs is immaterial. They may be of triangular or inverted-U-shaped section, or may be pipes merely with suitable perforations, provided, however, that the communication between the 10 reservoirs and carbureting-chambers is, preferably, at or near the bottom of the reservoirs. It is not necessary that the distributing-reservoirs should be located or arranged between the carbureting-chambers, as shown in the drawings.

15 The reservoirs may be arranged wholly without the carbureting-chambers, as at F', and distributing-pipes merely be employed to conduct and feed the hydrocarbon fluid to the 20 absorbents; or the reservoirs may be arranged wholly within the carbureting-chambers, thus combining the functions of distributing-pipes and reservoirs proper.

It will be observed that the relative dimensions of the compartments and of the reservoirs and carbureting-chambers increase from 25 above downward, in order that a greater quantity of liquid may be contained in the lower chambers, where the absorbing capacity of the 30 air is greatest, and consequently a larger amount of fluid is required to supply the requirements of use.

H is the filling-pipe and also the pump. It extends vertically through the carbureter into 35 the receiving-reservoir D to near its bottom. It is provided below with a valve, i, lifting upward, and at a point above the carbureting-compartment C is a side pipe, K, leading from the pipe H to and into the upper terminus of 40 the distributing-conduits F.

It will be observed that in filling the apparatus through the pipe H the valve i prevents the flow in that direction, and the liquid will pass through the side pipe, K, and thence 45 through the reservoirs F, through the carbureter into the tank D.

In the pipe H is placed a pump-rod carrying below a piston containing an upwardly-lifting valve, which thus constitutes the pipe 50 H a complete pump. By the use of this the chambers may be at any time replenished from the bottom of the tank D by a few strokes of the pump-rod, and any excess find its way back again to the tank by means of its overflow-pipes. This arrangement also furnishes a 55 means of ascertaining the exhaustion of the storage-tank always before the chambers are entirely exhausted, and thus gives plenty of time for a new supply, and the capacity of the 60 tank D being known, there need never be any excess of liquid placed in it.

A vent-pipe, L, by which air is permitted to pass out of the reservoirs in filling, is arranged alongside of the filling-pipe H, so that the plug 65 p, which constitutes the handle of the pump-

rod, also serves as a stopper to both pipes when out of use; or the vent-pipe may be provided with a stop-cock.

In the ordinary operation of the reservoirs the carbureted air passes in as the fluid passes 70 out, thus rendering the feeding action of the reservoirs entirely automatic.

I am aware that it is not new to arrange distributing-reservoirs adjacent to the carbureting-chambers for feeding purposes; also that 75 an overflow-tank has been arranged in connection with the chambers of a carbureting apparatus, with pumps for restoring the hydrocarbon fluid to the apparatus; and such, broadly, I disclaim.

Having described my invention, I claim and desire to secure by Letters Patent—

1. The carbureting apparatus consisting of a closed vessel divided by horizontal partitions into a series of carbureting-chambers 85 with a bottom reservoir, the chambers being provided with overflow-pipes communicating downward into the reservoir, in combination with a vertical pipe arranged within the vessel and extending from near the bottom of the 90 reservoir entirely through the chambers, provided with a lateral discharge-pipe into the upper carbureting-chamber and with a foot-valve and lifting-plunger, substantially as and for the purpose specified.

2. In a carbureting apparatus, the combination and arrangement in one vessel of a series of carbureting-chambers, one above another, divided by suitable partitions into a substantially continuous carbureting-passage and a 100 fluid-reservoir, and a storage-tank beneath, with which the fluid-reservoir communicates by overflow-pipes, substantially as set forth.

3. In a carbureting apparatus, the combination of a carbureting-passage or connected series of passages provided with capillary absorbent material, a feeding-reservoir adjacent thereto throughout and communicating by overflow with a reservoir, with a pump for replenishing the feeding-reservoir from the bottom of the overflow-reservoir, substantially as 105 and for the purpose specified.

4. The combination, in a carbureting apparatus, of a cylindrical vessel divided by horizontal partitions into a bottom reservoir, a series of carbureting-chambers, and a condensing-chamber, the carbureting-chambers being vertically divided into a substantially continuous air-passage opening into the condensing-chamber above and into fluid-reservoirs communicating by overflow-pipes with bottom chamber or reservoir, substantially as specified.

In testimony whereof I have hereunto set my hand in the presence of two subscribing witnesses.

WILLIAM WEST.
